(57) **CLAIM**

I claim the ornamental design for an anamorphic sculpture, as shown and described.

DESCRIPTION

FIG. 1 is a top-front-right perspective view of an anamorphic sculpture;

FIG. 2 is a top-left-front perspective view thereof;

FIG. 3 is a bottom-front-right perspective view thereof;

FIG. 4 is a front view thereof, with the characteristic feature of which resides in showing the number “3”;

FIG. 5 is a rear view thereof;

FIG. 6 is a right view thereof, with the characteristic feature of which resides in showing the letter “D”;

FIG. 7 is a left view thereof;

FIG. 8 is a top view thereof; and,

FIG. 9 is a bottom view thereof.

Broken lines in the drawings depict boundaries of the anamorphic sculpture and form no part of the claimed design.
